UNITED STATES PATENT OFFICE

2,617,961

ELECTRON TUBE FOR VERY HIGH FREQUENCIES

Lothar Brück, Paris, France, assignor to Compagnie Générale de T. S. F., a corporation of France

Application December 27, 1947, Serial No. 794,143
In France January 8, 1947

9 Claims. (Cl. 315—3)

1

My invention relates to improvements in so-called travelling wave electron tubes. It is well known that in the said tubes the electrons are submitted to a speed modulation by an electric field propagated approximately at the speed of the said electrons. The speed of propagation of the field is much lower than the speed of the light. The slowly propagating field is produced within a helix of a very small pitch.

With such a device, a short wave amplification cannot be obtained at will. When the diameter of the helix is smaller than a quarter wave-length, the field within the helix becomes too weak because the field lines produced along the axis of the helix by the various parts of one single turn or spire are in opposition and thus are partially destroyed.

My invention is intended for overcoming that drawback. For that purpose, two plane spirals, shown in elevation and plan view in Fig. 1, are set opposite in two parallel planes and excited in phase-coincidence, a result that can be obtained by connecting their extremities. Because of this sort of excitation, no electric field exists between the opposite surfaces in each spiral. If a wave is brought into A, it will travel through as far as E. There exists, however, a radial electric field between the successive turns of one same spiral, as shown in the Fig. 2 wherein have been drawn, in sectional view, a few turns of spires of each one of the two spirals S₁ and S₂. Axially disposed with regard to the common axis of both spirals is shown the cathode K (Fig. 1), surrounded by a grid G carried to a positive potential with reference to the cathode. After having run through that grid, the electrons enter the space comprised between the two spirals at a uniform speed. By an appropriate choice of the grid potential, the electrons are made to move, in the space contained between the two spirals, at such a speed that they always meet approximately with the same field. With regard to the electrons, everything occurs as if the electric field was moved approximately at electron speed along the direction of the ray. For that reason a gathering or "grouping" of the electrons is observed, as is the case within the helix of a conventional travelling wave tube.

Contrary, however, to what occurs in a usual travelling wave tube, a grouping of the electrons, in the tube made according to my invention, only exists in definite zones along the periphery of the turns or spires, while the phases of the waves in the intermediate zones are inconsistent with such a grouping of the electrons. The existence

2

of such zones is due to the fact that an equal angular length of run of the wave along a turn does not correspond to an equal length along the said turn when starting from two different points of that turn. Thus can be observed a grouping of the electrons only in angular sectors determined by a length of run of the wave consistent with a grouping of electrons having a given speed. In the grouping or concentration sectors, the electrons are speed modulated when crossing the turns of the spiral in the neighborhood of the cathode, and they transfer energy to the wave in the outer parts of the spiral, where the amplified wave can be collected.

Fig. 1 also shows the energy lead-in channel in the form of a coaxial cable of which the inner conductor C₁ may be the extension of one of the two spirals and the outer conductor R₁ is joined to the envelope. The channel is also shown in the form of a coaxial energy evacuation line of which the inner conductor C₂ is connected to the two spirals, and the outer conductor R₂ is joined to the envelope.

Instead of the two spirals disposed in parallel positions, it is obviously possible to make use of a guide bent into spiral form (Fig. 3) excited by the wave of the H₁₀ type. For enabling the electrons to pass through the guide, this latter is cut out along L as shown in Fig. 3. With reference to an orthogonal section of the bent guide, the lines of the electric wave field have a radial direction, i. e. the same direction as the electrons which move in the disc cut out in L (Fig. 3).

Whether in the case of the two parallel spirals or in the case of the guide bent in the shape of a spiral, it is of advantage to use a constant magnetic field, the lines of field of which follow the radial direction in order to permit the electrons to be deviated and caught by the turns of the spiral or by the walls of the guide. Such a magnetic field can be produced by means of a magnet shaped as the magnetic structures used in the dynamic loud-speakers.

Fig. 3 shows in perspective one form of tube embodying my invention, the view being cut by its median plane. In the center of the tube at K is the emissive cylindrical cathode surrounded by the grid G formed of metallic bars equally distributed on a cylindrical coaxial to said cathode. At W may be seen the focalizing wehnelt of said electronic beam. At P are the walls of the guide split along the arrow L, the walls being rectangular and wound in spirals. At A and E are shown, in the form of rectangular guide sections, the energy inlet and evacuation channels.

For securing a selective amplification, the space surrounding the cathode must be, according to the invention, divided up into sectors consistent with a suitable grouping of the electrons for a given frequency. Only the sectors having suitable phase relations will be travelled through by the electrons; and in the other sectors there will be no electrons. That division into sectors can be determined by means of bars or rods B (Fig. 4) carried to a negative potential with regard to the cathode K and placed before or behind the positive grid G. The bars B are parallel with the cathode K. Fig. 4 is a view similar to Fig. 3, with parts designated by the same reference letters, showing a tube according to the invention equipped with these bars B. When wishing to change the frequency intended to be amplified, it is sufficient to simply displace the bars on the circle on which they are disposed.

In the elevational portion of Fig. 1 there is shown by way of illustration a system N_1, N_2 formed of two solenoids in opposition, capable of establishing the radial magnetic field heretofore described. I have designated the connection to the inner end A of the spiral through a coaxial cable R_1, C_1 similar to the coaxial cable R_2, C_2 where the outer conductor R_1 connects with the envelope M and the inner end conductor C_1 connects to the inner terminal of the spiral S_2 .

Another process for changing the frequency to be amplified consists in displacing the sectors containing the electrons by carrying the bars B to different potentials. Indeed by changing these potentials it is possible to displace the sectors of grouping so as to obtain a frequency variation.

For obtaining a low electron speed, it is possible to concentrate the electric fields in the slits F of the guide (Fig. 5). For this purpose the slits are made narrower by means of spiral plates applied against the cut-out edges along L in the guide Figs. 3 and 5). Under these conditions, the transit time in each one of the slits becomes small enough to permit the transfer of energy from the electrons to the wave in each one of the slits considered alone. In order that the energy transfer be effected in all the slits, it is moreover necessary to adjust the transit time in the spaces of the guide free of any field. This is accomplished by controlling the D. C. voltage applied to the guide, so that the electrons meet with the same phase relations when passing successively in front of all the slits.

Fig. 5 shows a perspective view of a non-limiting example of a form of tube having such slits F. The figure shows the tube in perspective cut by a median plane. In the center of the tube at K, is the emissive cylindrical cathode, surrounded by the grid G formed of metallic bars likewise distributed on a cylinder co-axial to said cathode. At W I have shown the focalizing wehnelt of the electronic beam. The walls of the rectangular guide are split and wound in spirals as shown at P. A and E designate respectively rectangular guides serving as energy inlet and evacuation channels.

Lastly, by introducing reactive coupling means in their connections, the above described tubes can be used as oscillators.

What I claim is:

1. A traveling wave tube comprising a retardation line in the form of two flat spirals disposed facing each other in two parallel planes and each having an input situated near their center and an output situated at the external turns of said

spirals, means comprising an ultra-high frequency conduit coupled with said input for injecting therein ultra-high frequency waves for the two spirals situated near their center, means for injecting into the space between these spirals an electron beam emanating from the center of the spirals and directed along their radii, and means for giving to the beam of electrons a velocity substantially equal to the apparent velocity of phase propagation of the wave in the radial direction.

2. A traveling wave tube as set forth in claim 1, wherein the conductor of the spirals has a hollow cross section adapted to guide the ultra-high frequency wave.

3. A traveling wave tube as set forth in claim 1, wherein the means for injecting the beam comprise a cathode situated in the center of the spirals and surrounded by a grid connected to a source of positive potential relative to the cathode.

4. A traveling wave tube as set forth in claim 1 in combination with means for applying a constant magnetic field whose lines of force follow the direction of the radii of the spirals.

5. A traveling wave tube as set forth in claim 1, wherein the conductor of the spirals has a hollow cross section adapted to guide the ultra-high frequency wave, the interior of the guide being separated from the circulation space of the beam by a partition having a spiral-shaped slot.

6. A traveling wave tube as set forth in claim 1, with means for cutting up the electronic emission into a plurality of radial beams.

7. A traveling wave tube as set forth in claim 1, wherein the emitting system of the beam comprises a cathode surrounded by a network of bars connected to sources of negative potential relative to the cathode and serving to cut up the electronic emission into a plurality of radial beams.

8. A traveling wave tube, as set forth in claim 1, wherein the emitting system of the beam comprises a cathode surrounded by a network of bars connected to sources of negative potential relative to the cathode and serving to cut up the electronic emission into a plurality of radial beams, and means for making the potentials of these bars vary.

9. A traveling wave tube as set forth in claim 1, wherein the emitting system of the beam comprises a cathode surrounded by a network of bars connected to sources of negative potential with respect to the cathode and serving to cut up the electronic emission into a plurality of radial beams, said bars being equally spaced in a circular path.

LOTHAR BRÜCK.
